ROAD ROLLER

Raymond W. Keeler, Galion, Ohio, assignor to
The Galion Iron Works & Manufacturing
Company, a corporation of Ohio

Application February 25, 1937, Serial No. 127,719

5 Claims. (Cl. 262—8)

This invention relates to a road roller and particularly to a road roller including a scarifier attachment.

An object of the invention is to provide an improved road roller construction in which the scarifier will be relieved by movement of the roller frame in case it strikes an immovable obstruction.

Another object of the invention is to provide a simple, yet efficient, means to determine variably the depth which the scarifier teeth will penetrate the road surface.

Other objects of the invention will appear hereinafter, the novel features and combinations being set forth in the appended claims.

In the accompanying drawings,

Fig. 1 is a side elevational view showing a road roller comprising my invention;

Fig. 2 is a side elevational view showing the rear end of the road roller with the scarifier illustrated in its operative position;

Fig. 3 is a side elevational view of a portion of the road roller taken on the opposite side from the illustration of Fig. 2 with the proximate rear roller removed and with a part of the main frame side plate cut away to illustrate more clearly the frame mounting; other parts of the roller also being omitted in the interest of clearness;

Figs. 4 and 5 placed end to end comprise a plan view of the road roller comprising my invention;

Fig. 6 is an end elevational view of said device;

Fig. 7 is a sectional elevational view taken on the line 7—7 of Fig. 6 looking in the direction of the arrows;

Fig. 8 is an end elevational view of the adjustable shoe for the scarifier;

Fig. 9 is a detail sectional view showing the mounting means for one of the arms of the parallel link mechanism;

Fig. 10 shows a hydraulic system for controlling the steering and the operation of the scarifier of the road roller;

Fig. 11 is an end elevational view of a modified form of my invention;

Fig. 12 is an end view of the scarifier of Fig. 11; and

Fig. 13 is a sectional view taken on line 13—13 of Fig. 11 looking in the direction of the arrows.

This application is a continuation in part of my application for a Road building machine, Serial No. 676,906, filed June 21, 1933.

The road roller comprising my invention is formed by a main frame 20 comprising a pair of spaced parallel longitudinally extending side

plates 21, 21 which are rigidly attached to a head or steering post casting 22, as by rivets. Adjacent the rear end and bottom of said side plates 21 I provide a platform 23 which is rigidly attached to said side plates, as by welding.

Adjacent the front end of the road roller I provide a front roller 24 which operates not only to roll a surface over which the roller operates, but also to provide for the steering of the road roller and the supporting of the front end thereof. Said front roller 24 is rotatably mounted in a yoke 25 pivotally attached to an upwardly extending post 26 by a pin 126 providing for tilting of said roller 24 about a horizontal, normally longitudinally extending axis as provided by said pin 126. Said post 26 is resiliently supported in the head casting 22 by a plurality of coil springs 27 which are spaced around the post 26 and are mounted in appropriate cups carried by a plate 28, which plate 28 rests upon a flange at the base of the post 26. It is thus seen that the main frame 20 is both resiliently and pivotally supported upon the front roller 24.

Forward and rearward scrapers 29 and 30 are provided to free the front roller 24 of any material which may tend to adhere thereto.

To provide for the steering of the road roller a lever, not shown, is splined to the top spline portion 31 of the post 26, which lever is operated by a hydraulic motor of the hydraulic system, hereinafter described in complete detail.

The driving unit for the road roller is entirely flexibly mounted with respect to the main frame 20, and to provide for this structure I provide an auxiliary frame 32, best seen in Figs. 4 and 5 of the drawings, which auxiliary frame is formed by a pair of longitudinally extending channel members 33 which are rigidly attached together across their fronts by an angle member 34, which angle member 34 is mounted upon coil spring 35 resilient supporting means 35 which, in turn, are mounted upon a transversely extending angle member 36 (Fig. 1), which angle member 36 is rigidly attached to and extends between the side plates 21 of the main frame 20.

Adjacent their rear ends the channel members 33 are rigidly attached to a casting 37 which forms a transmission gear housing for which housing a removable cover plate 38 (Fig. 5) is provided. The casting 37 is an elongated rearwardly extending casting which forms a part of the auxiliary frame 32 and also provides a differential housing 39 to house the differential gears and the reduction gears for driving the laterally spaced rear rollers 40.

The rear rollers 40 are mounted upon axles for rotation about a fixed axis with respect to the differential housing 39 and casting 37 by virtue of laterally extending hubs 41 which are rigidly attached to said casting 37 and which have appropriate anti-friction bearings cooperating with the axles of the rollers 40, one of which axles is seen at 410 in Fig. 3 of the drawings. The auxiliary frame 32 with the housings 38, 39 and the hubs 41, 41 all rigidly connected together, constitute a rigid unit in which the rear roller axles are journaled for rotation on an axis which is fixed relative to such rigid unit.

Extending laterally from the casting 37 are clutches 42 and 43. These clutches may be separably operable and when one of them is operated, the tractor will move in a forward direction and when the other is operated it will move in a reverse direction.

Adjacent the forward portion of the auxiliary frame 33, and rigidly mounted thereon, is an internal combustion engine 44 for driving the road roller. Said engine 44 is rigidly attached to the casting 31, and is also rigidly attached to the auxiliary frame 32. It is thus to be seen that the engine 44 and the gear housing, formed principally by the casting 31, are supported directly from the auxiliary frame 32, the rear end of said frame being in turn supported directly from the rear rollers 40. In consequence, an appreciable portion of the weight of the auxiliary frame 32 and the elements carried thereby, will be transferred to the road surface through the rollers 40. In other words, the rear end of the power transmission unit acts non-yieldingly through the rear traction rollers 40, 40 on material on the roadway. This is desirable as the rollers 40 preferably have a maximum crushing capacity.

While the rear end of such power transmission unit is non-yieldingly supported, the forward end of the auxiliary frame 32 is resiliently supported on the main frame 20.

To provide for a resilient support of the rear end of the main frame 20 on the auxiliary frame 32 of the power transmission unit, so that said rear end of the main frame 20 may yield upwardly with respect to the auxiliary frame 32 and the rollers 40, I provide a spring mounting between each of the hubs 41 and the side plates 21 of the main frame 20. As clearly seen in Fig. 3 of the drawings, each of the hubs 41 is provided with a pair of upper and lower cups 45 and 46, respectively, adapted to receive coil springs 47 and 48, respectively.

The hubs 41 are preferably square and are adapted to reciprocate vertically in the guide means provided on the side plates 21, the structure of one of which is clearly seen in Fig. 3. Said guide means comprises upper and lower and side angle members 49, the upper and lower angle members being provided with bosses which extend into the coil springs 47 and 48, said coil springs 47 and 48 resting upon the inwardly extending horizontal flanges of said upper and lower angle members 49. It will thus be seen that the side members 21 of the main frame 20 are resiliently supported upon the hubs 41.

Mounted upon the forward end of the main frame 20 is a radiator 50 for the engine 44. An appropriate hood 51 is also provided for the motor 44 as well as the other mechanism carried by the auxiliary frame 32, which hood 51 at its rear end is also carried by the main frame 20.

A dash board 52 is provided at the rear end

of the hood 51 upon which dash board is mounted the usual control means, such as a steering wheel 53, a brake lever 54, and the other usual control members.

An operator's seat 55 is resiliently supported upon the platform 23 in proper position for the operator to reach the control elements of the road roller.

Mounted upon the rear end of the main frame 20 is a scarifier mechanism 56 comprising a transversely extending cylindrical tube 57 of heavy material, to which is attached a pair of spaced brackets 58, 58 (see Fig. 6), said brackets being formed by a pair of similar parallel plates 59, 59 which are rigidly attached to the tube 57, as by welding. The brackets 58 are so positioned with respect to the longitudinal axis of the tube 57, that any force transmitted to said tube 57 through a bracket 58 will be at substantially the center of the forces acting upon the tube 57 when performing a scarifier action. This will be described more in detail hereinafter.

Cooperating with each of the brackets 58 is a pair of parallel links 60, which links are pivotally attached to the brackets 58 by appropriate pins 61 (see Fig. 7) provided with retaining cotter pins. Each of the links 60 is pivotally attached to a side plate 21 of the main frame adjacent the rear end portion thereof at which the platform 23 is attached thereto, to provide free swinging movement of said links 60. The specific structure which provides for this free pivotal movement is best seen by reference to Fig. 9 of the drawings. As here disclosed, a stub shaft 62 is provided with a central integral flange 63 and 35 with a pair of screw threaded end extensions 64 and 65. The stub shaft 62 is clamped rigidly with the side plate 21 and a flange of the platform 23 by a nut 66 which clamps the side plate 21 and flange of the platform 23 rigidly between the flange 63 and the washer 66. Thus the stub shaft 62 is rigidly attached to the main frame 20.

The link 60 is provided with a cylindrical opening which is received upon a cylindrical portion 45 of the stub shaft 62, which portion has a width slightly greater than the thickness of the link 60, and a retaining washer 68 and nut 69 prevent the link 60 from coming off the stub shaft 62 while providing free movement with respect thereto. It will be understood that each of the links 60 is attached to the main frame 20 by a stub shaft construction of the type shown in Fig. 9.

To provide for the vertical adjustment of the scarifier 56, there is provided a cross-piece 70 which extends between the brackets 58 and has stub shafts 71, 71 rigidly attached to said cross-piece 70 and pivoting in appropriate apertures in the brackets 58, whereby said cross-piece 70 may rotate with respect to the brackets 58 along its longitudinal axis. A piston rod 72 is pivotally attached to the center of the cross-piece 70 by a pin 73, (Fig. 6), preferably retained in place by appropriate cotter pins. It will be understood that the upper end of the piston rod 72 is provided with an appropriate piston 74 (Fig. 10), which piston 74 works in a hydraulic cylinder 75, which cylinder is pivotally attached to a bracket 76 by a pin 76, said bracket 75 being rigidly attached to the platform 23, as by appropriate nuts and bolts. (Figs. 1 and 2).

Adjacent each end of the tube 57 of the scarifier mechanism 56 I provide an adjustable shoe mechanism or gauge, best seen in Fig. 8 of the drawings, for adjustably determining the extent

to which the scarifier teeth enter into the road surface which is to be torn up. Each of said adjustable gauges is formed by an upstanding channel member 71 provided with a row of spaced apertures 78 and having a road engaging shoe 79 at the bottom thereof, the forward and rearward ends of which are up-turned to provide a skid to slide easily over the road surface.

The tube 57 is provided with a number of aligned apertures adapted to receive the reversible scarifier teeth 80 which are rigidly held in position by bolts 81 which fit into notches in the sides of said teeth 80. The teeth 80 preferably make an angle of approximately 45 degrees with the vertical and this angle will be constant for any position of adjustment of the scarifier mechanism 56 due to the provision of the parallel link mechanism formed by the links 60. It will be evident that the extent to which the teeth 80 enter the road surface in operation will be determined by the adjustment of the gauge or skid comprising the channel member 71. There is, of course, such a gauge at each end of the tube 57.

Referring particularly to Fig. 6 of the drawings, it is to be noted that the hold-down force which will be transmitted to the scarifier mechanism 56 by the piston rod 72 will be distributed by the cross-piece 70 to the tube 57 through the brackets 58. The forces on the two sides of the tube 57, taking the pin 73 as a pivot point, will be equalized due to the fact that said tube 57 can pivot about said pin 73. Furthermore, the forces transmitted to the tube 57 through the brackets 58 will be equalized on each side of said brackets. It is to be noted in this connection that, by considering either half of the tube 57, the bracket 58 is located essentially at the center of this half of said tube 57, and that there are two teeth 80 on each side of said bracket 58. As a consequence, the cross-piece 71 will be effective to distribute the hold-down forces substantially equally to the tube 57, and thus there will be no unusual strain on any portion of said tube.

It is furthermore to be particularly noted that the scarifier mechanism 56 is attached to the main frame 20, which main frame 20 does not need to partake of the movement of any of the rollers, and particularly does not need to partake of the movement of the rear rollers 40. As a consequence, when an immovable object is encountered by the scarifier in operation, the scarifier mechanism can yield either upwardly or downwardly as permitted by the springs 47, 48 without requiring movement of any of the rollers, and particularly without requiring movement of the rear rollers 40. This provides a safety feature to protect the scarifier should an immovable object be encountered.

Furthermore, the spring mount of the rollers at 47, 48 provides for a more even operation of the main frame 20 in that should one of the rollers encounter a rough spot in the road surface it may roll over it without requiring a proportionate movement of the main frame. This makes for more uniform operation of the scarifier in case the roller is operating on a rough road surface. In other words, the springs 47, 48, between the main frame 20 and hubs 41, 41, of the roller traction unit, serve to permit the scarifier to ride over obstructions in the roadway without interfering with the operation of the rollers, and the latter may ride over irregularities in the roadway without disturbing the operation of the scarifier.

In place of the adjustable gauges above de-

scribed, I may employ anti-friction or roller type of adjustable gauges, as illustrated in Figs. 11, 12 and 13 of the drawings. In this form there are provided two of such gauges, one at each end of the tube 57, said gauges being of similar construction.

Each of said roller gauges comprises a supporting plate 140 rigidly attached to an end of the tube 57, as by welding. Pivoted to the plate 140 by a bolt 141 (see Fig. 12) is a carrier plate 142 provided with a stub shaft 143 upon which is supported a road engaging wheel or roller 144. The carrier plate 142 is provided with a plurality of apertures 145 (see Fig. 12) the centers of which are on the arc of a circle having its center along the axis of bolt 141. The carrier plate 142 is also provided with a pair of apertures which may be aligned with selected apertures 145. A pair of bolts 146 provided with appropriate nuts, extend through the said pair of apertures and through selected apertures 145 to hold the carrier plate 142 in adjusted position.

It is manifest that by removing the bolts 146 on which the wheels 144 are journaled, the carrier plate 142 may be swung about the bolts 141, thereby adjusting the elevation of the tubular carrier 57 and consequently the depth of penetration of the scarifier teeth 80. It is evident that by tightening the nuts on the bolts 141 and 146, the carrier plate 142 will be clamped rigid with the supporting plate 140.

Referring to Fig. 10 of the drawings, there is disclosed a hydraulic system for controlling the steering of the road roller and the operation of the scarifier mechanism. As disclosed in said Fig. 10 of the drawings, a continuously operable gear pump 90 is provided which is continuously driven from the engine 44. The in-put to said pump is connected to an oil reservoir 91 by a pipe 92. The out-put of said pump 90 is connected to a main pressure pipe 93, which pressure pipe 93 leads to a plurality of control devices, including a control valve 94 for the hydraulic piston 74 of the scarifier mechanism, a control valve 95 for the steering mechanism and a regulator 96. A return pipe 97 leads from each of the mechanisms 94, 95 and 96 to the oil reservoir 91. When the control valves 94 and 95 are in their non-operative position, as illustrated in Fig. 10 of the drawings, the pressure pipe 93 will be blocked at each of said control valves 94 and 95. Under such conditions the regulator 96 operates to provide a substantially no-load by-pass for said pump 90.

Attention is directed to the structure of the regulator 96 which provides this no-load by-pass. Said regulator comprises a main casting 98 having an inlet port 99 connected to the pressure pipe 93 and an outlet port 100 connected to the return pipe 97. A piston 101 is mounted in a cylinder in the casting 98 and is provided with a head 102 adapted to close the port 99 when the piston is in its lowered position, to which it is urged solely by gravity. However, when pressure is present in the pressure pipe 93, which is transmitted to the head 102 and no counter-pressure is applied to overcome this pressure, the piston 101 will be lifted, as illustrated in Fig. 10, providing a direct communication between the ports 99 and 100, and thus providing a direct by-pass for the pump 90. Once this by-pass is formed it will require a very little amount of work to keep the piston 101 in its elevated position, and thus the pump 90 operates at substantially no-load.

The top end of the piston 101 is in communication with a chamber 103 formed in the casting 98

having communication with a pipe 104. When either of the control valves 94 and 95 is operated to adjust its corresponding hydraulic motor, as hereinafter described, pressure in the pressure pipe 93 will be supplied to the pipe 104 and will act upon the top of the piston 101. The top of the piston 101 has a slightly greater area than the bottom, and this, coupled with the fact that gravity tends to pull the piston 101 downwardly, will operate to close the by-pass whenever pressure is supplied to said line 104, as aforesaid.

The regulator 96 also provides a high pressure relief so that in case an excessive pressure is present in the pipe 104, it will be relieved. Such pressure might be created, for example, by a piston motor reaching the end of its stroke with the control valve therefor in the operating position. Said high pressure relief is formed by making the piston 101 of hollow construction with a relief port 105 communicating with the outlet port 100. Within the hollow piston 101 is a normally closed valve formed by a ball 106 and a thimble 107 providing a seat therefor. A spring 108 urges the ball 106 upwardly to maintain the entrance to the hollow piston 101 normally closed. However, upon the presence of an excessively high pressure in the pipe 104, the fluid therein will flow through the thimble 107 and force the ball 106 downwardly, escaping through the port 105 into the outlet port 100, thereby to relieve the excessive pressure.

Referring to the structure of the control valve 94 which controls the hydraulic piston motor for operating the scarifier and having the cylinder 14 and the piston 12, said valve comprises a casting 110 having a large discharge chamber 111 connected to the return pipe 97, and providing a central boss 112 with a pressure chamber 113 and control chambers 114 and 115. The control chambers 114 and 115 are connected to control pipes 116 and 117, respectively, leading to the bottom and top, respectively, of the cylinder 14, thereby to control the movement of the piston rod 12 by acting upon the piston 118 associated therewith. Said chambers 114 and 115 surround control cylinders 120 and 121, respectively, which are formed integral with a control rod 122.

Reciprocal motion of the control rod 122 is controlled by a pivoted lever 123 having a handle 124. A packing gland 125 is provided to allow reciprocation of the rod 122 without losing any oil from the discharge chamber 111. With the valve 94 in the position illustrated in Fig. 10 of the drawings, the pistons 120 and 121 will effectively seal the ends of the pipes 116 and 117 and thus will lock the piston 118 in its adjusted position with the cylinder 14 and the pipes 116 and 117 entirely filled with oil. That is, the cylinder 14 will be filled with oil both above and below the piston 118 and both of the pipes 116 and 117 will be filled with oil. The scarifier will thus be locked in any adjusted position against movement either upwardly or downwardly. To move the scarifier upwardly the lever will be operated to move the control rod 122 to the left, as viewed in Fig. 10. Under such circumstances the pressure pipe 93 will be effectively connected to the pipe 116 through the chambers 113 and 114, and the control pipe 117 will be connected to the return pipe 97 through the chambers 111 and 115. A reverse movement of the control rod 122 will result in the connection of the pressure pipe 93 and the control pipe 116, and the connection of the control pipe 116 and the return pipe 97 in an obvious manner. Thus the scarifier mechanism may be

raised or lowered and locked in any adjusted position.

In order to close the previously mentioned bypass for the pump 90 when the control valve 94 is operated in either direction to adjust the scarifier, the pipe 104 leads to a tube 126 which extends into a bore in the rod 122. This tube 126 has a pair of ports 127 and 227 to receive fluid from the chamber 113. The rod 122 is also provided with a port 128. When the rod 122 is moved to the left, as viewed in Fig. 10, ports 127 and 128 are in communication, and thus liquid under pressure in the chamber 113 will flow into the tube 126 and to the pipe 104 to close the by-pass of the regulator 96, as previously described. When the rod is moved to the right, as viewed in Fig. 10, the ports 128 and 227 will provide communication between the tube 126 and the chamber 113 to produce a like result. It thus clearly appears that upon the operation of the control valve 94 in either direction, the regulator mechanism 96 will immediately close the no-load by-pass for the pump 90, thus providing pressure in the pressure pipe 93 to effect the operation of the scarifier.

To provide for the steering of the road roller, a hydraulic piston motor having a cylinder 130, a piston 131, and a piston rod 132 is provided, said rod 132 cooperating with a lever pivotally attached to the splined portion 31 of the post 26, as previously mentioned. Control pipes 133 and 134 are provided for the cylinder 130 and lead to the control valve 95. The control valve 95 has substantially the same structure as the control valve 94 and therefore will not be described in detail. However, said control valve 95 may have an enlarged casting 135 to receive oil which may be filled at any time through the fill cap 135' to replace any oil lost from the hydraulic system. In addition, the control rod 136, which is similar to the control rod 122 of the valve 94, is operated from the steering wheel 53 by the interposition of a cam mechanism, not shown, which is effective to translate rotary motion of the steering wheel 53 into reciprocatory motion of the control rod 136. The steering wheel 53 is spring biased to a normal position which will return the control rod 136 to the position illustrated in Fig. 10. It will be evident therefore that the control valve 95 may be operated by the steering wheel 53 to turn the steering roller of the road roller 50 and to lock said steering roller in any desired position of adjustment. The hydraulic control system is also preferably provided with a pressure gauge 137 connected with the pipe 104 to indicate pressure in said system.

It should be particularly noted that as shown in Fig. 5 there is sufficient looseness in the pivotal connections between the rear ends of the parallel links 60, 60 and the two pairs of spaced plates 59, 59, to permit limited tilting of the elongated scarifier holder 57 and the teeth carried thereby so that adjustment of the gauges at the ends of the holder can be relied on to predetermine the crowning of the roadway by the scarifying operation. That is to say, while the roller is traveling along a hard-surfaced roadway abnormally crowned, the scarifier may be held down to its work in accordance with the adjustment of the end gauges to enable the scarifier to tear up the hard surface for re-crowning in accordance with modern practice. The tilting adjustment is on the axis 73 shown in Figs. 6 and 11, this axis extending longitudinally of the road roller.

It should also be observed that the pivotal connection between the lower end of the piston 75

rod 72 and the scarifier holder 57 is effected by means of an equalizer which is pivoted at 71, 71 for rocking movement relatively to the carrier 57 on an axis parallel thereto and parallel to the pivot 76 shown in Figs. 1 and 2. By referring to Figs. 1, 2, 6 and 7, it will be seen that the two pairs of plates 59 are secured to the tubular holder 57 so as to extend radially therefrom. The ends of the equalizer 70 are journaled at 71, 71

10 to the pairs of plates 59, 59 as shown in Fig. 6, and the parallel links 60, 60 of the parallel motion mechanism are pivoted at 61, 61 to the pairs of plates 59, 59, as shown in Figs. 6 and 7.

The scarifying teeth 80 are reversible so that both ends can be used, and each tooth 80 is provided with a plurality of spaced lateral notches 80', 80' so that these teeth may each be held in adjusted position relative to the tubular holder 57 so as to project at various distances therefrom. During operation of the scarifier the adjustment of the end shoes or end rollers relative to the tooth holder 57, predetermines the transverse tilting of the holder on the axis 73, and when the scarifier is in operation the parallel links 60, 60 of the parallel motion mechanism act as draft devices for pulling the teeth along the roadway surface with a scarifying action. Meanwhile the hydraulic motor holds the scarifying teeth down to their work with the end gauge shoes or end rollers firmly pressed against the road surface. Although the hydraulic motor 74 is pivoted at 76, the scarifying teeth can not be moved upwardly relatively to the main frame because the piston 118 (Fig. 10) is locked in adjusted position by the locking of the liquid in the passageways as illustrated in Fig. 10.

Inasmuch as the hydraulic motor is applied at the central point 73 through an equalizer 70 to the road engaging shoes or rollers at the ends of the carrier 57, the hold-down force is equally distributed all along the row of scarifying teeth. This arrangement affords a very rugged construction which is capable of withstanding severe forces encountered in performing scarifying operations. However, if the scarifying teeth meet with immovable obstructions which causes the main frame to be moved upwardly, such upward movement will be cushioned by the shock absorbing springs 48 of Figs. 1 and 2. Furthermore, such shocks due to the scarifying teeth engaging immovable obstructions in the roadway, will be absorbed by the springs 35, 35 between the forward portion of the main frame and the forward portion of the traction unit which comprises the engine, the rear traction rollers and the power transmission mechanism between the engine and these rollers.

It will also be observed by referring to Figs. 1 and 2, that when such immovable obstruction in the roadway has been passed over by the scarifying teeth, the sudden downward movement of the rear portion of the main frame will be cushioned by the upper springs 47. The lower springs 48 are relatively short but if the immovable obstruction in the roadway is relatively high, such springs 48 after being fully compressed, may act as a fulcrum for pivotal movement of the whole main frame on the axis of the rear traction rollers, with the result that the springs 27 between the front end of the main frame and the steering roller unit will act to co-operate with the springs 48 in cushioning the shock due to the scarifier teeth riding over an unusually high immovable obstruction in the roadway. It will thus be seen that all of the springs 47, 48, 35 and 27 co-

operate to prevent shock and jar from being transmitted to the engine when the scarifier teeth ride over an immovable obstruction in the roadway.

It is desirable that the rear traction rollers have a direct connection to the engine on fixed axes relative thereto, but the vibrations due to the traction unit traveling over the material to be rolled, is not transmitted directly to the operator at his station because the operator's station is on the rear end of the main frame and the latter is resiliently mounted by means of the springs 47 on the hubs 41, 41 of the traction unit, as illustrated in Fig. 5.

As shown in the drawings, particularly Figs. 1, 2 and 10, the hydraulic motor 74 for holding the scarifier down to its work, is controlled from the operator's station by means of the handle 124 and the lever 123. Also from the operator's station the steering of the road roller and scarifier is controlled by means of the wheel 53, as shown in Figs. 1, 2 and 10. The starting, stopping and control of speed of the engine is also effected from the operator's station, and inasmuch as the scarifier is directly under the operator's station it will be easy for him to glance down occasionally to observe the condition of the material being scarified and the extent of scarifying action.

Obviously those skilled in the art may make various changes in the details and arrangement of parts without departing from the spirit and scope of the invention as defined by the claims hereto appended, and I therefore wish not be restricted to the precise construction herein disclosed.

Having thus described and shown an embodiment of my invention, what I desire to secure by Letters Patent of the United States is:

1. In a road working machine, the combination with a vehicle, of a scarifier, spaced apart parallel motion devices connecting said scarifier to said vehicle for adjustment in elevation relative thereto, said parallel motion devices being adapted to serve as draft connections between said holder and said vehicle, adjustable ground engaging supports connected to the ends of said scarifier, mechanism for holding said supports in adjusted positions to predetermine the transverse inclination of the scarifier in operation, a fluid pressure motor pivotally connected to said vehicle on an axis extending transversely of the vehicle and pivotally connected to said scarifier on an axis extending longitudinally of the vehicle, and means for controlling said motor to hold the scarifier down to its work at the aforesaid transverse inclination to effect scarifying operations in accordance with the desired crowning of the roadway.

2. A scarifier comprising an elongated holder, teeth mounted thereon, spaced-apart pairs of spaced-apart plates mounted on said holder to extend radially therefrom, an equalizer pivoted at its ends to said pairs of plates, parallel motion mechanism connected to said pairs of plates and adapted to serve as draft connections to a draft vehicle, and means pivotally connected to said equalizer intermediate the ends thereof on an axis extending longitudinally of the vehicle to adjust the elevation of the said holder and its teeth.

3. A scarifier for road working apparatus comprising an elongated holder, scarifying teeth carried by said holder, spaced-apart pairs of spaced-apart plates connected to said holder to project radially upward therefrom, an equalizer pivotally connected at its ends to said plates to

rock relatively thereto on an axis spaced from but parallel to said holder, a fluid-pressure motor pivotally connected to said equalizer intermediate the ends of the latter, and spaced-apart parallel motion devices connected to said pairs of plates and adapted to serve as draft connections to a draft vehicle.

4. A scarifier comprising an elongated holder, scarifying teeth carried thereby, spaced-apart depth gauge ground engaging shoes adjustably mounted on said holder, spaced-apart parallel motion devices pivotally connected at their rear ends to said holder, said parallel motion devices being adapted to serve as draft connections between said holder and opposite sides of a draft vehicle forwardly of the rear end thereof, an equalizing device pivoted to said holder to rock relatively thereto on an axis parallel to said holder, a supporting bracket adapted to be mounted at the center of the rear end of such draft vehicle, and a reciprocating fluid pressure motor comprising a depending piston rod having its lower end pivoted to said equalizing device on an axis extending longitudinally of the vehicle, said motor also comprising a cylinder pivotally connected at its lower end to said support-

ing bracket on an axis extending transversely of the rear end of the vehicle.

5. The combination with a vehicle frame, of a supporting bracket thereon, an elongated holder, scarifying teeth carried by said holder, spaced-apart brackets on said holder, parallel motion mechanism connecting said brackets to opposite sides of said vehicle frame forwardly of the rear end thereof, an equalizing bar pivoted at its ends to said brackets in spaced relation to said holder to rock on an axis parallel to said holder, a reciprocating fluid pressure motor comprising a cylinder pivotally connected to said supporting bracket on an axis extending transversely of the rear end of the vehicle frame, said motor also comprising a depending piston rod pivotally connected to said equalizing bar intermediate the ends thereof on an axis extending longitudinally of the vehicle frame, adjustable ground engaging shoes at the ends of said holder to predetermine the transverse inclination of the holder in operation, and means for controlling said motor to hold the scarifier teeth down to their work at the aforesaid transverse inclination to effect scarifying operations in accordance with the desired crowning of the roadway.

RAYMOND W. KEELER.
